WITNESS: John E. Kelly

James J. Gramma.
INVENTOR
BY Victor J. Evans

ATTORNEY

UNITED STATES PATENT OFFICE.

JAMES JOSEPH GRAMMA, OF NEW YORK, N. Y.

CIRCUIT CLOSER.

Application filed January 17, 1921. Serial No. 437,860.

To all whom it may concern:

Be it known that I, JAMES JOSEPH GRAMMA, a citizen of the United States, residing at New York city, in the county of New York and State of New York, have invented new and useful Improvements in Circuit Closers, of which the following is a specification.

This invention relates to improvements in circuit closers for automobiles for automatically indicating when it is attempted to steal the car.

One of the principal objects is to provide a device of this kind with means which may be set so that upon operation of the driving shaft, the alarm will be automatically set into operation.

Another object is to provide novel means for "setting" the mechanism.

Another object is to provide novel means for preventing operation of the alarm when the machine is in normal operation.

With these and other objects in view which will be more apparent as the specification proceeds, the invention resides in certain construction and combination and arrangement of parts, the essential features of which are hereinafter fully described, particularly pointed out in the claim, and illustrated in the accompanying drawing, in which:—

Figure 1 is a top plan view of my improved alarm with the cover removed.

Figure 2 is a vertical sectional view substantially on line 2—2 of Figure 1.

Figure 3 is a detail view of the pin-receiving block.

Like characters of reference refer to like parts in all views.

Referring to the drawing in detail, 10 represents a main casing or frame-work which is preferably in the form of a box through which a shaft 11 passes. This shaft may be either the main drive shaft of the machine or may be a shaft geared thereto and driven thereby in the direction of the arrow. Mounted on shaft 11 is a sleeve 12 having a cam portion 13.

Secured to the inside of the box 10 is a pair of frame members 14 which are secured to the front and bottom of the box and extend rearwardly nearly to shaft 11. These frames have rigidly secured between them two cross plates 15 and 16 and a rod 17.

55 A plate 18 is provided at its ends with

pintles or dowels 19 which embrace the frames 14 and travel thereon as on a track. A similar plate 20 is similarly mounted on the opposite side of plate 15, and short rods 21 piercing member 15 rigidly secure members 18 and 20 to move together. A boss 22 is formed on the rear portion of plate 17 and to this boss is pivoted a pair of hooks 23 having rearwardly projecting cam faces 24. When plate 18 is fully rearward, hooks 23 are pulled up by a spring 25 until they catch on rod 17 and prevent return movement of member 18. Springs 26 tend constantly to return members 18 and 20 to normal position.

60 A rod or bar 27 is rotatably mounted in the front wall of box 10 and in the plate 16 and carries at its rear end a disk 28 provided with one or more forwardly projecting pins 29. A pin receiving collar 30 is secured to the wall 16 concentric with rod 27 and is provided with a number of pin receiving holes 31. These holes 31 are arranged very close to each other as shown in Figure 3, except at 32 where a small space is flat. The 65 free ends of pins 29 are pointed so as to slide into holes 31 unless seated directly against the portions 32.

A collar 33 is mounted on rod 27 and between this collar and the plate 16 is a spring 34 which tends constantly to force rod 21 toward the front of the box.

70 Rod 27 carries at its front end a knob or handle 35 by means of which said rod may be turned. The rod is also provided with 75 slot 36 in which is slidably mounted an indicating finger 37 which is pressed constantly against a dial plate 38 by a spring 39. This dial plate is marked off with graduations and the owner knows at which one of these 80 85 90 95 99 pins 29 are resting on portions 32.

An auxiliary casing 40 encloses the head 35 and adjacent parts and is closed by a door 41 provided with a suitable fastening 100 device.

Two batteries are shown at 43 and 44. A wire 45 connects one terminal of battery 43 with one of the binding posts of an alarm bell 46, and a wire 47 connects the 105 opposite pole of battery 44 with the remaining binding post of bell 46.

A contact strip 48 is mounted on the stationary frame member 15 and is connected by a wire 49 with the opposite pole of bat- 110

tery 44 from that to which wire 47 connects. Arranged facing contact strip 48 is a contact strip 50 secured to and movable with the member 18, and connected by a wire 51 5 with the opposite terminal of battery 43 from that to which wire 45 is connected.

In operation, when the operator is about to leave his car, he opens door 41 and presses in on knob 35 which moves frames 10 20 and 18 rearwardly so that hooks 23 catch on bar 17. He then turns knob 35 until pins 29 are not over the portions 32, but 15 are over the holes 31. The door 41 is then locked, and the alarm is set. Should it then be attempted to move the car away, shaft 11 will necessarily be rotated and cam 13 20 will strike noses 24 and release the hooks 23 from bar 15, so that the frames 20 and 18 will spring forward, pins 29 entering 25 holes 31. In this manner contact 50 is moved against 48 thereby closing the circuit and causing ringing of the alarm bell 46.

In order to prevent ringing of the bell when the owner returns and starts his car, 25 he first opens door 41 and turns knob 35 until pins 29 are over the portions 32. Upon rotation of shaft 11, the hooks 23 are knocked off bar 17, but frames 18 and 20 30 are permitted only a limited amount of movement until pins 29 strike parts 32 so

that contact 50 does not reach contact 48 and the circuit is not completed.

While I have described what I deem to be the most desirable embodiment of my invention, it is obvious that many of the 35 details may be varied without in any way departing from the spirit of my invention, and I therefore do not limit myself to the exact details of construction herein set forth nor to anything less than the whole 40 of my invention limited only by the appended claim.

What I claim as new is:—

A device of the class described comprising a cam mounted on the shaft of an automobile, a frame, a carriage mounted on said frame and slideable thereon, a trigger mounted on said carriage and operable by said cam, a contact mounted on said carriage, a stationary contact mounted on said frame, a collar mounted on said frame and a manipulative member including a plurality of pins for co-action with a plurality of apertures provided in the collar whereby the contacts are rendered operative and inoperative upon tripping of said trigger. 45 50 55

In testimony whereof I have affixed my signature.

JAMES JOSEPH GRAMMA.
